UNITED STATES PATENT OFFICE.

RICHARD HERZBERG, OF STETTIN, GERMANY.

FURNACE FOR BURNING FINE FUEL.

SPECIFICATION forming part of Letters Patent No. 700,198, dated May 20, 1902.

Application filed October 25, 1901. Serial No. 79,906. (No model.)

To all whom it may concern:

Be it known that I, RICHARD HERZBERG, engineer, a subject of the Emperor of Germany, residing at Stettin, Germany, have invented 5 certain new and useful Improvements in Furnaces for Burning Fine Fuel, of which the following is a specification.

The object of my invention is to provide a furnace for burning pulverized or fine fuel, so 10 constructed as to feed the fuel evenly to the grate, to utilize a maximum amount of the heat produced, and to prevent waste.

In carrying out my invention I form a combustion-chamber, preferably in thick walls of 15 masonry, and so arrange pipes for circulating water or steam in the combustion-chamber as to cause the fuel fed into the combustion-chamber at the top to be evenly distributed 20 on a grate or into the fire. Preferably the pipes are made to incase the combustion-chamber and to also extend transversely across it, so as to divide the entering fuel into a number of streams to be deposited upon the 25 grate, as before stated.

25 In the accompanying drawings, Figure 1 shows a vertical transverse section through a furnace embodying my improvements, and Fig. 2 shows a vertical transverse section of the same at right angles to that shown in 30 Fig. 1.

The combustion-chamber A is preferably formed in thick walls of masonry B. The grate C is located at the bottom of the combustion-chamber and over an ash-pit D. The 35 fuel is fed from a hopper E through a chute F to the upper end of the combustion-chamber, a rotary feeding device G being preferably employed to feed the fuel in small quantities at regular intervals. The device G may 40 be operated in any suitable way. The walls of masonry are preferably provided with passages I, through which air may circulate and which will prevent the radiation of heat. Air may be supplied to the grate by means of a 45 pipe J, having a rose K.

K' indicates a door through which access may be had to the grate.

Within the combustion-chamber are arranged a number of coils of pipe adapted to 50 convey steam or water. Preferably the pipe enters at L and is then coiled around inside the combustion-chamber, so as to incase it, the convolutions of the pipe being close to-

gether, as indicated. The pipe is then coiled back and forth transversely across the combustion-chamber, so as to traverse all portions thereof, leaving space, however, between the coils for the fuel to be supplied. After traversing the combustion-chamber the pipe passes out at M.

The apparatus may be used for heating water to supply hot water, or it may be used to produce steam. It is not absolutely necessary that the pipes should be arranged horizontally, as they may be arranged obliquely; 55 but they should be so arranged that the fuel passing down from the chute F shall come in contact with the pipes and be divided into a number of streams, so that it shall be supplied evenly to the grate.

I claim as my invention—

1. A furnace for burning fine fuel comprising a combustion-chamber having a feed-opening at the top, and pipes crossing the combustion-chamber at different levels below 75 the feed-opening, and also incasing the combustion-chamber and the pipes which cross it.

2. A furnace for burning fine fuel comprising a combustion-chamber having a contracted upper end, a grate placed in a contracted chamber below the combustion-chamber, a feed-hopper for feeding fine fuel into the upper end of the combustion-chamber, and water-pipes for the circulation of water 80 in the combustion-chamber which cross the combustion-chamber at different levels and which also incase the crossing pipes and are contracted in area at the upper end of the combustion-chamber.

3. A furnace for burning fine fuel comprising a combustion-chamber having a feed-opening at the top, a grate at the bottom of the combustion-chamber, water-pipes crossing the combustion-chamber at different levels directly below the feed-opening and in 85 different vertical planes in the combustion-chamber, and water-pipes surrounding the crossing pipes which extend from top to bottom of the combustion-chamber.

In testimony whereof I have hereunto subscribed my name.

RICHARD HERZBERG.
